CLAIM

The ornamental design for a telephone, substantially as
shown and described.

DESCRIPTION

FIG. 1 is a top plan view of a telephone showing my
new design;

FIG. 2 is a side elevation thereof;

FIG. 3 is a top front perspective view thereof, with the
handset in a separated position;

FIG. 4 is an elevation as seen from the opposite side of
FIG. 2; and

FIG. 5 is a rear elevation thereof.

FIG. 1

FIG. 2

FIG. 3

FIG. 4
